CLAIM

The ornamental design for a spork for noodles in broth, as shown and described.

DESCRIPTION

FIG. 1 is a top, front, left side perspective view of a spork for noodles in broth of the present invention;

FIG. 2 is a top plan view thereof;

FIG. 3 bottom plan view thereof;

FIG. 4 is a front elevational view thereof;

FIG. 5 is a rear elevational view thereof;

FIG. 6 is a left side view thereof, the right side being a mirror image of the left side; and,

FIG. 7 is a cross-sectional view, cut along the plane of the longitudinal centerline of FIG. 2.

1 Claim, 4 Drawing Sheets(56)
